UNITED STATES PATENT OFFICE.

EARL J. EARLY, OF PHILADELPHIA, PENNSYLVANIA.

DRAWING-BOARD.

1,080,269.

Specification of Letters Patent.

Patented Dec. 2, 1913.

Application filed April 25, 1912. Serial No. 693,169.

To all whom it may concern:

Be it known that I, EARL J. EARLY, a citizen of the United States, residing in Philadelphia, Pennsylvania, have invented 5 certain Improvements in Drawing-Boards, of which the following is a specification.

One object of my invention is to provide a drawing board with novel means for normally retaining a sheet or body of paper 10 or other material in a desired position; the arrangement and construction of its parts being such as to not only hold such material firmly and immovably in place but to also insure that after removal from the 15 board, it shall occupy the same angular position when replaced thereon.

Another object of the invention is to provide a novel device for clamping one edge or side of a body of paper to a drawing 20 board in order that said paper shall be firmly retained in a position ready for use, the arrangement of parts being such that the paper may be placed in or removed from its position on the board with the 25 greatest convenience and held by means in no way interfering with the use of drawing instruments, such as a T square or set square upon the surface of the board.

I further desire to provide a drawing 30 board which shall include novel means for holding drawing tools, paper and the like, in order to permit of their convenient transportation, and which shall have its parts so arranged that a T-square may be removably 35 attached to it so as to be carried therewith.

Another object of my invention is to provide a drawing board having a novel form 40 of paper clamping device of such construction as to constitute a part of, or be operationally associated with a movable structure forming with the body or main portions of the board, a container for drawing instruments, etc.; the invention contemplating novel means for holding the container closed 45 and retaining the clamping member attached thereto in its paper-engaging position.

These objects and other advantageous 50 ends I secure as hereinafter set forth, reference being had to the accompanying drawing, in which,

Figure 1 is a plan of my novel form of drawing board, showing it, with its clamping member in position to hold a sheet of paper; Fig. 2 is a plan illustrating the board with the clamping member and back in their open positions; Fig. 3 is a plan of the back of the board shown in Figs. 1 and 2; Figs. 4 and 5 are sections taken on the lines *a—a*, *b—b*, respectively Fig. 1; Fig. 6 is a transverse section of a slightly modified form of that part of the board employed as a container; Fig. 7 is a plan illustrating the construction of the means for detachably holding the 55 clamping member to the bottom of the board; Figs. 8 and 9 are plans illustrating the front and rear faces respectively of a slightly modified form of my invention; and, Fig. 10 is a vertical section of the board 60 shown in Fig. 8.

In the above drawings, 1 represents the body of the drawing board, which is braced or reinforced on its back face by two cleats 2, respectively placed adjacent its side edges. 75 The adjacent or inner faces of these cleats are longitudinally slotted for the reception of a back in the form of a slidable sheet 3, which in the preferred form of my invention, has connected to one edge a cross piece 80 4, extending across the space between the two cleats, the placing of the grooves in said cleats being such that this back 3, which is of some thin material such as stiff cardboard, fiber, sheet metal or the like, is spaced some 85 distance away from the rear face of the body 1. The opposite edge of this back 3 is fixed to a second cross member 5, which with the cross member 4, closes and completes the container formed by the body and said sheet. 90

To the front face of the cross piece 5 is fixed a clamping member 6 usually in the form of a wooden strip of the length and thickness of the body 1 and of any suitable width, it being noted that this clamping member is so mounted on the cross piece 5 that it lies in the plane of said body. For holding one edge of the clamping member 6 tightly and preferably yieldingly against the adjacent edge of the body 1, I mount on 95 those portions of each of the cleats 2 projecting beyond the clamping edge of the

body, some form of doubly inclined abutment, which in Fig. 2 takes the form of a strip of metal 7, arranged to project in angular form on the inner edge thereof. For 5 the sake of convenience, each strip is held at one end in a slot or recess in the end of its cleat 2, from which point it is extended outwardly and then back at an angle to the end of the cleat; passing over this and 10 thence down the outside edge thereof to the slot holding its opposite end. If desired this abutment or keeper may be given other forms such as that indicated at 7^a in Fig. 7, without departing from my invention.

15 For removably holding the clamping member 6 in place, any manually operative latch, or other device may be provided, and in the present instance I have employed a length of spring wire mounted in the back cross 20 piece 5 and so formed as to provide two finger operated members 8. A spring coil portion 9 connects said members with two latch members 10 which extend through or adjacent the cross piece 5 to the hollow or suitably recessed ends thereof, and these members 25 are turned over or formed to provide curved or inclined projecting parts capable of engaging the abutments formed by the strips 7, in order to hold the clamping member 6 tightly against the adjacent end of the board body 1.

There is thus provided a flat container 35 between the back member 3 and the body 1, which may be opened by squeezing together the finger members 8 so as to withdraw the latch portion 10 from engagement with the abutments provided by the strips 7. By means of said finger members the clamping member 6 may be then drawn away from 40 the board body 1, thus causing the back 3 with its two cross members 4 and 5 to slide out from under said body and permitting access to the interior of the container. A sheet of paper may now be prepared for application 45 to the board by turning over a narrow width of one of its edges at right angles to its general plane. Thereafter this narrow width may be permitted to extend over the top edge of the board body while 50 the main portion of the paper rests upon said body and the clamping member 6 may then be approached to its holding position, whereupon the yieldingly mounted catches 10, after being first forced into the cavities 55 in the cross bar 5 by means of the inclined parts of the abutments 7, are forced outwardly back of or under said abutments by the action of the spring coil 9. The parts are so designed that under these conditions 60 the clamping member 6 is held tightly against the narrow edge of the body of paper X which is rigidly and immovably held so that its main portion may be used in the customary manner.

By pinching or drawing together the finger members 8, the catches 10 may be withdrawn from the abutments 7, after which the member 6 may be drawn away from the board body 1 and the paper removed. A valuable feature of my invention resides in the fact that such a body of paper after being removed from the board, may be replaced thereon in an angular position absolutely the same as it originally occupied by reason of the alining action of its edge when gripped by the clamping member, so that any partially finished drawing may be continued without the necessity for "re-squaring" or possibility of its horizontal lines being other than at right angles to the reference edge of the board body.

For attaching a T-square to the drawing board for transportation or storage, I cut away the cleats 2 at points in line with each other as indicated in Figs. 3 and 4 in order 85 to permit the blade y of said T-square to enter the container formed between said cleats, the back and the board body, with its head y¹ in the position shown. In order to retain the T-square in place, I provide a 90 spring clip or other suitable holding device 11, mounting this preferably on one of the cleats 2 in such a position as to frictionally engage the end of the T-square blade.

In some cases the cross piece 4 may be 95 rigidly and permanently connected to the board body, as indicated in Fig. 6, in which case the back would merely slide into a groove in said cross piece from which it would be separated when the clamping piece 100 6 was moved away from the board body. Under ordinary conditions however, I prefer the construction shown in Figs. 2 and 5, whereby any articles in the container are 105 drawn toward the head of the board together with the back as this is moved outwardly from its closed position. Moreover, inasmuch as the T-square extends across the space within the container, the cross piece 4 in the construction shown in the 110 Figs. 3 and 4, would strike its blade after the back had been withdrawn a predetermined distance and thus prevent the accidental discharge of the contents of the container or the complete separation of the 115 back from the board body which might take place with that form of board shown in Fig. 6.

While I preferably employ a construction 120 of board having its paper clamping member 6 movable in straight lines from and toward the body, I may under certain conditions so arrange the parts that one end only of said clamping member may be moved or so that the clamping member may be hinged to the 125 board body and rotatable into and out of the plane thereof. In such a case while the front of the board would have the appear-

ance shown in Fig. 8, the cleat portion 2 on each side of the body 1, would be connected to an auxiliary cleat portion 2^a on one end of the clamping member 6 by means of a 5 U-shaped piece of spring wire 12 constituting a hinge arranged as shown in Fig. 9; it being understood that there would be the main and auxiliary cleats with their connecting U-shaped piece at each of the two 10 sides of the board structure. Inasmuch as the said piece 12 is made of relatively heavy, stiff wire, it at all times, holds the clamping member 6 with one of its edges pressed against the adjacent edge of the 15 board body 1.

In order to mount a piece of drawing paper on a board of this form, the clamping member 6 is bent backward out of the plane of the board body against the action of the 20 spring hinge 12, and one edge of the paper is placed in the space between it and the adjacent edge of said body. On being released said clamping member is brought back into the plane of the body by reason 25 of the action of the two spring hinges 12, and should the paper be of any unusual thickness, said member and the board body are free to separate for a greater or less distance as may be necessary by reason of 30 the bending of the side and back members of the spring hinges. If not previously bent the sheet of paper, after having its edge clamped as above noted, may be bodily moved down into engagement with the top 35 surface of the board body.

In order to insert the edge of a sheet of drawing paper between the board body 1 and the clamping member 6, it is not necessary to always bend back the latter, since 40 one or both ends of this may be pulled away from said body and the paper edge thereafter introduced into the space between these two parts.

By means of my invention, the drawing 45 tools ordinarily employed may be conveniently carried within the container provided at the back of the board and the T-square likewise attached by mounting it in the cleat openings, so that its extremity may engage 50 the spring holding clip 11. At the same time it is possible to conveniently attach or remove a piece of drawing paper in a minimum time without the necessity for thumb tacks or holding devices other than 55 the clamping member 6.

I claim—

1. The combination with a drawing board of means for holding paper thereon consisting of a member movably connected to the 60 board in position to clamp one edge of a sheet of paper between itself and an edge thereof; with a structure connected to said clamping member and coacting with the board body to form a container.

2. The combination of a drawing board; 65 a back slidably mounted on said board and forming a container therewith; a member connected to said back for clamping an edge of a body of paper to an edge of the board; and means for retaining said member in a 70 clamping position.

3. The combination of a drawing board having cleats along the opposite sides of its rear surface; a back slidably mounted on said cleats and cooperating therewith and 75 with the board to form a container; a paper clamping strip connected to and movable with said back, and means for actuating said strip to cause it to clamp a piece of paper to one edge of the board. 80

4. The combination of a drawing board; a clamping member movably mounted thereon; structures on the board forming holding abutments; and spring retaining means mounted on the clamping member in position to co-act with the abutments to hold 85 said member in position to grip a body of paper between itself and the adjacent edge of the board.

5. The combination of a drawing board 90 having cleats on its rear surface; inclined holding abutments mounted on said cleats; a clamping member; and releasable holding means carried by said member in position to coöperate with the abutments to force 95 the clamping member toward the board edge.

6. The combination of a drawing board having cleats on its rear surface; inclined holding abutments mounted on said cleats; 100 a clamping member; and releasable holding means carried by said member in position to coöperate with the abutments to force the member toward the board edge; with a back connected to said clamping member 105 and coöperating with the board to form a container.

7. The combination of a drawing board; a back coöoperating therewith to form a container; with a spring clip for holding a T- 110 square with its blade extending in position to prevent removal of said back from the board, while allowing its limited movement.

8. The combination of a drawing board having cleats provided with recesses for the 115 reception of a T-square adjacent the rear surface of the board; a back slidably mounted on the board and having a cross member fixed to it in position to be held from removal by a T-square mounted in the recesses 120 of said cleats, while having a limited movement relatively to said T-square; with means for normally retaining the back in its inner position.

9. The combination of a drawing board; 125 a clamping member mounted adjacent one edge thereof; a back rigidly attached to said clamping member and coöperating with

the board to form a container; with a device for holding the clamping member in its operative position; said device including a handle or handles available for use in without drawing the back.

10. The combination of a drawing board; an elongated bar forming a clamping member; a structure attached to said bar and guided on the back of the board to normally

form a container; and means for holding 10 the bar adjacent one edge of the board.

In testimony whereof, I have signed my name to this specification, in the presence of two subscribing witnesses.

EARL J. EARLY.
